Attorney.

UNITED STATES PATENT OFFICE.

JOHN W. CHERRY, OF NORFOLK, VIRGINIA, ASSIGNOR TO GREAT COUNCIL OF THE UNITED STATES OF THE IMPROVED ORDER OF RED MEN, A CORPORATION.

DESIGN FOR A BADGE.

No. 39,316.

Specification for Design.

Patented May 26, 1908.

Application filed February 17, 1908. Serial No. 416,428. Term of patent 14 years.

To all whom it may concern:

Be it known that I, JOHN W. CHERRY, a citizen of the United States, residing at Norfolk, in the county of Norfolk and State of Virginia, have invented a new, original, and ornamental Design for a Badge, of which the following is a specification, reference being had to the accompanying drawing, forming a part thereof.

The figure is a plan view of a badge, showing my new design.

I claim:

The ornamental design for a badge, as shown.

J. W. CHERRY.

Witnesses:

JOHN SCHOMAKER,
M. M. CHERRY.
